UNITED STATES PATENT OFFICE

FRED WEINDEL, JR., OF ALLENTOWN, PENNSYLVANIA, ASSIGNOR TO L. F. GRAMMES & SONS, INC., OF ALLENTOWN, PENNSYLVANIA, A CORPORATION OF MARYLAND

CARD-HOLDING DEVICE

Application filed March 12, 1926. Serial No. 94,139.

This invention relates to devices for clampingly holding cards, such for example as menus or advertising sheets, in vertical position so that their opposite sides are simultaneously displayed for ready reading at tables and counters of restaurants or stores.

In connection with a device of the kind referred to, I seek to obtain the advantages both of lightness and economy of manufacture attendant upon construction from sheet material, and notwithstanding structural lightness, to insure, on the one hand, stability of the device as a whole against being easily upset; but, on the other hand, to afford the card firm support against the possibility of displacement from a true vertical position relative to the holder.

In the drawings Fig. I is a perspective view of a card holding device conveniently embodying my invention, and showing the manner in which it is used.

Fig. II is a transverse sectional view of the same; and,

Fig. III, a similar view of an alternative form of my invention.

The structure of Figs. I and II, involves counterpart components 5, 6 that are fashioned from sheet material, preferably sheet metal of uniform width throughout. These components 5, 6 each afford a spring clamping jaw 7 of angular formation, and a short vertical segment 8 beneath said jaw with an outwardly extending lateral flange 9. In assembling, the components 5, 6 are placed back to back so that their vertical segments 8, 8 are brought into abutting relation, whereupon they are permanently secured together preferably by means of tubular rivets such as shown at 10, 10, through said vertical segments. By virtue of alignment as a result of assembling of the parts 5, 6 as just described, the flanges 9, 9 jointly constitute an extended base for supporting the device with ample stability against being easily upset. For convenience of ready insertion of a card or sheet 11 between them after the manner illustrated in Fig. I, the upper ends of the clamping jaws 7, 7 are rounded as at 12, 12. In this connection it is to be particularly noted that at the 50 region of emergence with the clamping jaws

7, 7 the segments 8, 8 are curved somewhat with resulting provision of a crotch or wedge-like seat 13 to take the bottom edge of the card.

The alternative construction of Fig. III is 55 similar to the first described form of my invention in that it is characterized by the opposing clamping jaws 7, 7, and the vertical web afforded by the abutting segments 8, 8 intermediate the jaws and the lateral base 60 flanges 9, 9. However, in this instance, the device is made from a single strip of sheet metal instead of two as before, the method of bending being obvious from the illustration and entailing doubling or retroverting of the 65 metal upon itself throughout the extent of the base flanges 9, 9. In the latter construction, riveting may be entirely dispensed with as sufficient reliance may be placed upon the 70 springiness and set of the metal to hold the device to the intended configuration.

From the foregoing, it will be apparent that the card holding device of my invention is neat and attractive in appearance, and adapts itself to ready and economic manufacture. 75 Moreover, notwithstanding its lightness, the device is quite stable against being easily upset, and, by reason of its capacity to firmly engage the display card at spaced intervals, insures maintenance of the latter against displacement from true upright position. 80

Having thus described my invention, I claim:

1. As a new article of manufacture a holding device for supporting a menu card in true 85 vertical position constructed of sheet material to provide opposed upwardly-directed angular-form spring-clamp jaws with the entrant ends in cooperative engagement and an intervening wedge-like seat afforded by convergently rounding of the jaws at their lower 90 parts into mutually abutting sections, said sections terminating in co-planar base flanges that project laterally outward in reverse directions from the longitudinal median of the 95 device.

2. As a new article of manufacture a holding device for supporting a menu card in true vertical position constructed of a single strip of sheet material to provide opposed angular 100

form spring-clamp jaws with the entrant ends in cooperative engagement and to grip the card at a distance remote from a wedge-like seat for its lower edge afforded by convergently rounding of the jaws at the bottom, and co-planar base flanges formed by retroversions in the strip material, said flanges projecting laterally outward from the longitudinal median of the device at a short distance below the clamp jaws with integral vertical abutment segments intermediate the flange and jaw portions, said abutment sections being permanently connected by tubular rivets.

15 In testimony whereof, I have hereunto signed my name at Allentown, Pa., this 8th day of March, 1926.

FRED WEINDEL, JR.
